UNITED STATES PATENT OFFICE.

DEARELL D. SHIERK, OF ROCKFORD, ILLINOIS, ASSIGNOR OF ONE-THIRD TO WILLIAM J. STEWARD, OF ROCKFORD, ILLINOIS.

BOILER CONSTRUCTION.

1,136,374.

Specification of Letters Patent. Patented Apr. 20, 1915.

Application filed January 5, 1915. Serial No. 625.

To all whom it may concern:

Be it known that I, DEARELL D. SHIERK, a citizen of the United States, residing at Rockford, in the county of Winnebago and State of Illinois, have invented certain new and useful Improvements in Boiler Construction, of which the following is a specification.

This invention relates in general to steam boilers and more particularly to locomotive boilers and more specifically has reference to the construction of and the connections between the fire box sheet and the surrounding boiler shell.

In locomotive boilers as customarily constructed the walls of the fire box, the top of which is commonly referred to as the crown sheet and the sides as the side sheets, are securely connected to the surrounding boiler shell by stays and braces designed to preclude deformation of the sheets under pressure. The stays, commonly known as stay bolts, are customarily threaded through alined tapped holes in the boiler shell and fire box sheets, the inner ends of the bolts being then riveted over against the inner face of the sheets.

The expansion and contraction of the sheets from exposure to the high temperature in the fire box and the strains to which the sheets and the stay bolts are subjected by the high boiler pressure and as the result of vibration of the engine and the shocks and jars incident to the running of the locomotive cause the metal of the sheets around the holes through which the stay bolts pass to crystallize and diminish in strength, the stay bolts have a tendency to work loose in the sheets, thereby resulting in leakage around the bolts from the boiler into the fire box. And if the bolts are tightened up by further riveting their inner ends, as is customarily done, the blows of the riveting operation tend still further to crystallize the sheets so that sooner or later the sheets will fracture and crack around the stay bolt holes, thus necessitating a renewal of the sheet at very great expense.

One of the primary objects of my present invention is to obviate the objections above mentioned which are inherent in boilers as

ordinarily built, by providing a boiler construction embodying imperforate crown and side sheets so that these sheets will not be weakened by stay bolt holes but will possess 55 and retain their original strength.

Another object of my invention is to securely attach the stay bolts to the imperforate crown and side sheets without insertion through the sheets, this object being attained by securing the stay bolts to the outer faces only of the sheets in a novel manner, to be later more fully explained.

Another object of the invention is to rigidly connect the stay bolts both with the 65 boiler shell and the fire box sheets without riveting the bolts, thereby eliminating not only the riveting operation itself but also obviating the weakening and crystallizing of the metal which inevitably results from 70 the blows of the riveting hammer.

A further object of the invention is to increase the efficiency of the boiler by increasing the radiating surfaces of the side and crown sheets, the radiating surfaces of 75 which are materially decreased in the ordinary boiler construction by the heads of the stay bolts on the inside of the fire box.

Still another object is to provide a boiler construction in which the stay bolts can be 80 quickly and easily removed and replaced for purposes of repair entirely from outside the boiler and by one man, thus effecting a material saving in time and labor over the constructions now in use, which require the 85 services of two men, one on the outside of the boiler and one on the inside of the fire box, in order to remove a broken or weakened stay bolt and replace it by another.

Other objects and many practical advantages of my invention will be readily appreciated by those skilled in the art as the invention is more fully understood by reference to the following description when considered in connection with the accompanying 95 drawings.

Referring to the drawings - Figure 1 is a fragmentary cross sectional view of a locomotive boiler embodying my invention; Fig. 2 is an enlarged view showing the details of 100 my improved construction, and Fig. 3 is a view taken on the line 3--3 of Fig. 2.

By reference to Fig. 1 of the drawings it will be observed that reference character 5 indicates the shell of a boiler surrounding the fire box 6, the walls of which, comprising 5 the crown sheet 7 and the side sheets 8, will be hereafter referred to as the fire box sheets. In this as in other boiler constructions the fire box sheets and the boiler shell are connected together and reinforced at frequent 10 intervals by stay bolts arranged substantially as shown in Fig. 1.

Instead of making holes in the fire box sheets and extending the stay bolts through them and riveting over the inner ends of the 15 bolts as has heretofore been done, with the consequent weakening of the sheets as has been previously explained, I make provision for attaching the inner ends of the stay bolts to the outer faces only of the sheets by 20 punching out from the body of the metal of which the sheets are composed, a plurality of hollow nipples 9 as shown in Fig. 2. One of these nipples is formed for each stay bolt and after the nipples have been punched out 25 they are threaded exteriorly as indicated by reference character 11.

The boiler shell 5 is provided with tapped openings 12 corresponding in number and location with the nipples 9, the openings 30 being of sufficient size to permit the insertion therethrough of the enlarged hollow heads 13 of the stay bolts 14. The stay bolt heads 13, which are preferably circular in cross section, are hollowed out or cupped, as 35 shown in Fig. 2, and interiorly threaded as indicated by reference character 15 to fit the threads 11 on the nipples 9 so that the bolts may be fixedly and rigidly but yet detachably secured to the fire box sheets by threading 40 them onto the outwardly projecting nipples 9.

The outer ends of the stay bolts 14 are threaded as indicated by 16 and a rigid connection is established between the stay bolts 45 and the boiler shell by means of rings or bushings 17, tapped to fit the stay bolt thread 16, and exteriorly threaded to be screwed into the boiler shell holes 12. The outer ends of the bushing 17 are squared as indicated at 50 18 to receive a wrench, by means of which the bushings are screwed into position. The stay bolts are preferably formed with a central bore 19 to provide the required telltale 55 hole through which escaping steam or water will call attention to a broken or cracked bolt.

In assembling my improved construction after the fire box sheet has been positioned and riveted in place by the usual rivets 60 around its periphery the stay bolts are inserted through the shell holes 12 from the outside and threaded onto the nipples 9. Any suitable tool of well known construction may be employed for screwing the bolts 65 tightly onto the nipples. The bushings 17

are then threaded onto the outer ends of the bolts and into the tapped openings 12 to thereby rigidly connect the stay bolts with the shell. It will thus be manifest that the stay bolts can be quickly and easily connected up by one man outside the boiler. All riveting of the bolts with its attendant disadvantages is eliminated and the necessity for a man to enter the fire box is obviated. When repairs or replacement of a 75 stay bolt become necessary the old bolt can be quickly and easily removed by unthreading the bushing 17 and unscrewing the bolt from its nipple.

So far as I am aware I am the first to provide a locomotive boiler construction embodying imperforate crown and side sheets so that the sheets possess and retain full and original strength of the metal. It is to be understood that the crown and side sheets 80 are, strictly speaking, not imperforate for the reason that they are provided with the usual riveting holes around their peripheries for the accommodation of fastening rivets, but the sheets are imperforate except for 85 these marginal riveting holes, and as distinguished from the sheets heretofore used the word "imperforate" correctly describes my novel sheets.

It should be manifest that the imperforate 90 sheets shown and described possess much greater strength than the old style sheets having holes through which the stay bolts extend; that the radiating surface of the sheets is materially increased over the radiating surface of the old style sheets which were reduced in radiating efficiency by the ends of the stay bolts projecting therethrough, and that in my present construction even if the threads by which the stay bolts 100 are connected to the sheet nipples should become worn or corroded so as to permit leakage of water or steam past them such leakage would do no harm as the boiler contents could not escape into the fire box.

My improved construction is strong, durable, cheap and efficient and materially reduces the expense of repairs on the locomotive both because of the longevity of the original construction and because of the saving in time and labor required in making 110 repairs when such become necessary.

Obviously the details of construction illustrated and described are capable of considerable modification and variation without departing from the essence of this invention, as set forth in the appended claims.

I claim:

1. A boiler construction comprising an imperforate fire box sheet, and means attached to the outer face of said sheet at intervals throughout its area for holding said sheet against deformation.

2. A boiler construction comprising an imperforate fire box sheet provided on its 130

outer face with a plurality of integral nipples, and means attached to said nipples for holding said sheets against deformation.

3. A boiler construction including an imperforate fire box sheet provided on its outer face with a plurality of exteriorly threaded nipples.

4. A boiler construction comprising an imperforate fire box sheet provided on its outer surface with threaded nipples, and stay bolts having their inner ends in threaded engagement with said nipples.

5. A boiler construction comprising an imperforate fire box sheet, a boiler shell, and means attached to the outer face of said sheet without passing through the sheet and connected with said shell whereby said sheet is held against distortion.

6. A boiler construction comprising a fire box sheet provided on its outer surface with a plurality of nipples a boiler shell provided with openings arranged in alinement with said nipples, stay bolts connected at their

inner ends to said nipples, and means for connecting the outer ends of said stay bolts 25 with said shell.

7. A boiler construction comprising a fire box sheet provided on its outer surface with a plurality of nipples, a boiler shell having openings arranged in alinement with said 30 nipples, stay bolts having their inner ends threadedly engaged with the nipples, and bushings threadedly engaged with the outer ends of said stay bolts and with the walls of said shell openings.

8. A boiler construction comprising a fire box sheet provided on its outer surface with a threaded nipple, a stay bolt having an enlarged tapped inner end threadedly engaged with said nipple, a boiler shell, and a bushing rigidly connected with said shell and with said bolt.
